UNITED STATES PATENT OFFICE

FRANK J. REICHMANN, OF CHICAGO, ILLINOIS

LOUD-SPEAKER

Application filed May 6, 1926. Serial No. 107,046.

This invention relates to sound reproducing devices, and more particularly to a reproducing device of the so-called "cone" type, wherein a tympanum of comparatively large area is employed.

Reproducers, in general, are divided into several types, but fall principally in the "horn" type and the "cone" type. The latter is conceded to effect more efficient reproduction over a wide range of "voice" frequencies than the horn type, but it possesses an undesirable tone characteristic which the horn within its most efficient range does not have. For this reason many people have continued 10 to use the horn type of speaker in radio reception in spite of the fact that the horn can be designed to reproduce faithfully only within a comparatively narrow field.

The object of the present invention is the 20 provision of a cone-type sound reproducer which in large measure will be free from the undesirable tonal characteristics of the cone and which will faithfully reproduce sounds having widely divergent frequencies.

25 A reproducer embodying the main features of the present invention is provided with a tympanum of large area comprising a flat annular portion and a cone portion, which cone portion may be integral or adhesively secured to the interior edge of the annular portion. The size of the tympanum and the relative dimensions of the two portions thereof are arranged in accordance with certain characteristics which will be explained more 30 in detail hereinafter.

35 A sound reproducing device is operably mounted with respect to the cone speaker and has its tone arm adjustably secured to the apex thereof.

40 Other objects and features of the invention will be apparent from a consideration of the following detailed description, taken in connection with the accompanying drawings, in which

45 Figure 1 is a front elevational view of an instrument embodying the main features of the invention, part of the front grill being broken away to illustrate some of the internal structural details;

Figure 2 is a rear elevational view of the same speaker;

Figure 3 is a sectional view taken on the line 3—3 of Figure 1, looking in the direction of the arrows; and

Figure 4 is a fragmentary elevation of a portion of the margin of one type of cone.

Referring now to the single sheet of drawing made a part of this specification and in which identical parts in the several views are designated by the same reference characters, the speaker comprises a tympanum generally designated by the reference character 10, said tympanum comprising a flat, annular portion 10^a and a cone portion 10^b.

The tympanum 10 may have an added rim portion 10^c which may comprise an annular metallic member, or a similar member of other material. It may also be produced by building up the rim with materials applied thereto. Its purpose is to reinforce the margin of the tympanum and to stretch the material thereof. By stretching the material thereof and by adding to its mass, it regulates and controls the pitch of the tympanum 10.

50 Any suitable means may be employed for attaching the ring 10^c where made separately from the tympanum 10. Synthetic processes of a number of types may be employed to build up the rim material. It is also possible that the reinforcement may be formed as an integral part of the material of the tympanum 10.

55 As a specific example of the manner in which the reinforcement on the exterior portion of the rim may be obtained I have found that I get uniformly good results by the use of any one of the following procedures. A single sheet of paper cut to form a ring may be adhesively secured to one side of the periphery of the rim portion. Substantially the same procedure can be resorted to and a reinforcing section of paper in ring form secured to both sides of the ring portion.

60 Instead of ordinary mucilage I have employed a varnish of phenolic condensation product in its intermediate stage and subsequently reduced it to its final stage by heat and pressure to obtain a substantially homog-

enous final structure. An alternative use of phenolic condensation product is to simply coat the periphery of the rim portion with the varnish and then reduce the condensation product to its final stage, thus forming a thin reinforcing layer of phenolic condensation product on each side of the periphery of the rim.

The material secured to the edge as intimated need not be fibre in its character at all.

10 It may be a molding compound employing the usual gums such as kauri, copal, damar or such materials as rubber, gutta percha, balata, or combinations of these. When using the latter type of material the impregnation of the edge of the rim with latex thereon and subsequently vulcanizing the solid constituent of the latex can be resorted to.

15 As a still further example, sheets of metal 20 may be secured to the edge of the rim either by clamping or by the employment of any other suitable means, including gluing, whereby the reinforcement can be kept in place.

25 In addition to the rim structure just described, which is optional in the structure now to be set forth, the invention relates particularly to the shape and size of the tympanum. Obviously some supporting structure is necessary, and in the present instance I 30 have designed a supporting structure which is novel in design and of particular utility in mounting a tympanum of the type disclosed, and which is also a part of the subject matter of this invention.

35 A cylinder or hoop-like ring 11 is secured to a base 12 by any suitable means. The base 12 comprises a composition of material adapted to be molded when plastic, which 40 forms the outer portion of the base and is designated 12^a. Within the molded portion 12^a is a block of wood or other suitable material 12^b. Through this wooden base 12^b are screw holes through which screws 13 pass 45 to secure the frame 11 to the base 12. Felt may be used to cover the bottoms of base portions 12^a and 12^b, the latter being undercut to provide room for heads of screws 13, which pass upwardly through block 12^b.

50 A plurality of grooves 14—15 are arranged about the inner surface of said hoop-like member 11 at equal distances apart to form parallel tracks or seats. The cone 10 is disposed within the hoop-like member 11 and 55 is compensatingly secured between a pair of annular members 16 and 17 seated in said tracks 14 and 15.

Felt rings 19 and 20 preferably adhesively secured to members 16 and 17 are placed between the annular members 16 and 17 and the portion 10^a or 10^c of the cone. Other material than felt may be used for the cushion rings 19 and 20 and these may be secured other than by an adhesive. In this way it 65 will be seen that the cone 10 is secured in

the frame between pads or cushions whereby a sufficiently secure construction is obtained but a rigid fastening for said cone 10 is avoided. The cone 10 is adapted to slide or slip about between the felt rings 19 and 20 permitting compensation for jarring and strains during shipping and improving the character of its sound reproduction. There is no opportunity for the cone to rattle or make mechanical noises.

70 In order to afford a mounting for the telephone unit which is referred to generally by the reference character 25, a grille construction is employed, said grille consisting of a single U-shaped member 26 having diverging arms 27, said arms 27 being riveted or otherwise secured at their ends which have upturned flange portions 28 to the frame 11. Screws may be employed for attaching the grille 26. A transverse bar 28 having flanged ends 28^a may be used to secure to said upright members the telephone unit 25 to the grille 26, screws or rivets being adapted to pass through the member 26 and said flanges.

75 Said telephone unit 25 may be of any usual design, but it is arranged so that the armature or moving element thereof can be secured to the cone 10 at its apex in order to impart vibrations thereto. To illustrate 80 one mode of making said connection, Figure 3 shows a connecting rod 30 secured to the apex of the cone by means of an adjusting nut 31. The usual small metal cones 32 and 33 are employed to reinforce the apex of the cone 10^b and afford a better connection for the connecting rod 30, while any suitable means such as a cone shaped nut 34 may be provided on the inner portion of said connecting rod 30 whereby said cone may be clamped in order to afford a tight engagement thereof.

85 In the means which is employed for supporting the members 16 and 17 in clamping relationship, it is unnecessary to insert fastening means through the tympanum 10. This is a decided advantage both in structure and in reproduction. I have shown in the drawings the structure which I prefer to use in order to accomplish this result. It will be 90 noticed that the rings 16 and 17, which I have described, are slip rings.

95 When rings having overlapping ends are desired, a pair of annular interior indentures such as are shown in Figure 3 are provided in the hoop-like ring 11. The members 16 and 17 when made with overlapping ends may be so arranged that one has a plain aperture therein and the other a threaded aperture. By expanding the members 16 and 17, made 100 as last described and securing the ends together by means of screws, these members may be securely retained in the hoop-like ring 11. When desired the annular tracks 14 and 15 may be omitted and the expansion of the 105

rings 16 and 17 may be used to secure retention without the necessity of employing any other fastening means.

A handle 37 may be provided at the uppermost portion of the instrument and may be secured in any suitable manner and may have any desirable contour. I prefer, however, to mount it on the member 17 as shown in Figure 2 in order to exclude it from view when facing the front of the instrument. In order to present a pleasing appearance, as well as to permit the sound to travel readily in both directions, I place a grille 40 over the face of the cone, said grille 40 preferably being confined within the hoop-like member 11 and secured to the fastening members 15 by machine screws 41-41.

The relative size of the different portions of the tympanum has a very great effect upon the results obtained therewith. I have found that a cone having a diameter of not less than six-tenths of the overall diameter of the tympanum, nor more than eight-tenths thereof, when used in accordance with the present invention, gives very good tonal results. The altitude of the cone should also be at least one-third the diameter.

To illustrate, in my preferred form of tympanum, the entire overall diameter of the portion 10^a, which is held between the clamping members 16 and 17, is approximately thirteen and one-quarter inches, the diameter of the cone about eight and three-quarter inches, and the height thereof about three and one-half inches. Numerous experiments seem to show that these approximate dimensions are the best, but I find that I can obtain fairly good results if the diameter of the cone is not more than eight-tenths, nor less than six-tenths of the overall diameter of the tympanum, and if the altitude of the cone is not less than one-third the diameter of the base.

The material of the cone, as intimated in a prior paragraph, may vary, depending upon the particular characteristics desired. For example, the material employed in the cone portion and annular portion may differ, or the same material may be employed and the thickness thereof vary. Of course the material for both parts may be exactly the same. With the mounting which I have shown and the preferred shape and size of the tympanum, I have found that I obtain the best results by using a thin varnished good rag paper, relatively light in weight, but possessing considerable mechanical strength.

The tympanum may be formed in a single piece from pulpy material, or it may be formed from sheet material, cut into the proper figure and adhesively secured to produce the structure pictured. I prefer this latter type of construction because a thinner and stronger cone can be produced since the cone portion may be secured to the annular portion so firmly as to result practically in a single

unitary structure. Moreover, this structure is apt to be much more economical and from the point of view of a manufacturer it is to be preferred for this reason as well.

In the foregoing description I have laid particular stress upon the size and shape of the tympanum which I employ and have described in detail the means for holding it in operable relation to a telephone unit. Although particularly good results are obtained by a combination such as this, it is obvious that some of these features may be employed independent of the others. For instance, I could employ different mounting for the tympanum and still obtain good results, while the structural details of the mounting would have great utility independent of the type of cone employed. I do not wish, therefore, to be bound by the particular description of these features, but I wish the invention to be limited only as defined by the scope of the appended claims.

The sliding of the tympanum within the frame saves tremendous losses in shipping. There is no necessity to rigidly secure the rim of the tympanum in the frame or in adjusted relation to the unit to obtain good reception. A freedom of movement is necessary to compensate for jars and strains incident to handling.

An added advantage of the ring construction here described is rapidity of assembly, coupled with the probability of no error in connection therewith.

I claim:

1. In a cone type sound reproducer, a composite tympanum having a flat, annular portion, and a central conical portion, annular non-vibrating members secured in compensating relationship to the periphery of said annular portion, and means for imparting vibration to said composite tympanum, and in which said non-vibrating members comprise a pair of annular metal members having a facing of felt disposed adjacent said tympanum.

2. In a cone type sound reproducer, a composite tympanum having a flat, annular portion, and a central conical portion, annular non-vibrating members secured in compensating relationship to the periphery of said annular portion, and means for imparting vibration to said composite tympanum, and in which said conical section is secured at its base to the interior edge of the annular portion and in which a telephone unit is provided with an actuating rod, said rod being adjustably secured to the apex of said conical section.

3. In a cone type sound reproducer a tympanum about thirteen and one-quarter inches in diameter, having a flat, annular portion, and a conical section secured to the interior edge of the annular portion, said conical section having a base approximately eight and one-half inches in diameter.

three-quarters inches in diameter and an altitude of about three and one-half inches, and combined with said tympanum a sound reproducing device adjustably secured to the apex of said conical section.

5 4. A reproducer as defined in claim 3, in which said conical portion and said flat, annular portion are formed of a different type of material.

10 5. In a sound reproducer of the class described, a tympanum of conical configuration, a hoop-like member having interior annular indentures therein, a pair of clamping members secured in said indentures and holding 15 said tympanum therebetween, and means for causing a vibration of said tympanum.

20 6. A sound reproducer as defined in claim 5, in which a brace is secured to the interior portion of said hoop-like member and in which the means for imparting vibration to said 25 tympanum comprises a telephone unit secured to said brace member.

25 7. A reproducer as defined in claim 5, in which said tympanum comprises a flat, annular portion secured between said clamping members, and a central conical section secured thereto.

30 8. A sound reproducer as defined in claim 5, in which said tympanum comprises a flat, annular portion, and a conical portion, the altitude of said cone being at least one-third of the diameter of the base thereof.

35 9. A reproducer as defined in claim 5, in which said tympanum comprises a flat, annular portion, and a conical portion, in which said conical portion is not less than six-tenths the entire available diameter of the tympanum.

40 10. A reproducer as defined in claim 5, comprising a flat, annular portion and central conical portion, the cone portion being not more than eight-tenths the entire available diameter of said tympanum.

45 11. A reproducer as defined in claim 5, in which said tympanum comprises a flat, annular portion and a central conical portion, in which the diameter of said conical portion is not more than eight-tenths the entire available diameter of said tympanum, and in 50 which the altitude of said cone is at least one-third the diameter of the base thereof.

55 12. In a cone type speaker, a frame having tracks, rings disposed in said tracks, and a tympanum movably disposed intermediate said rings.

60 13. In a cone type speaker, a frame having a track forming portion, guide members in said portion, a tympanum disposed between said guide members, and a cushion intermediate said guide members and said tympanum.

65 14. In a cone type speaker, a frame having tracks, ring members frictionally held in said tracks, and a tympanum slidably disposed intermediate said rings.

70 15. In a loud speaker of the cone type, a

frame, a tympanum disposed in same frame, and a base for said frame, said base comprising a body portion, means for securing said body portion to said frame, and an external portion of a material adapted to be applied to 70 said body portion in a plastic condition.

75 16. In a loud speaker of the cone type, a frame, a tympanum disposed in same frame, and a base for said frame, said base comprising a body, means for securing said body portion to said frame, and an external shell upon said body and adapted to be applied thereto while in a plastic condition, said shell being adapted to reduce vibration in said body portion.

80 FRANK J. REICHMANN.
